UNITED STATES PATENT OFFICE.

GEORGE C. ANTHON, OF NEW YORK, N. Y., ASSIGNOR TO STANLEY INSULATING COMPANY, OF GREAT BARRINGTON, MASSACHUSETTS, A CORPORATION OF MAINE.

HEAT-INSULATED RECEPTACLE.

1,426,446.

Specification of Letters Patent. Patented Aug. 22, 1922.

Application filed November 1, 1919. Serial No. 335,126.

To all whom it may concern:

Be it known that I, GEORGE C. ANTHON, a citizen of the United States, residing at New York, in the county of New York and State 5 of New York, have invented certain new and useful Improvements in Heat-Insulated Receptacles, of which the following is a specification:

This invention relates to thermally insulated receptacles of the type generally known 10 as vacuum bottles and particularly to those in which the spaced shells of the receptacle are made of metal, such as steel, joined together at the neck of the bottle as by means 15 of welding. This joinder of the inner and outer shells provides in effect a thermal bridge between the two shells across which a transfer of heat may take place, and which therefore detracts to a certain extent from 20 the efficiency of the device.

One of the objects of my invention is to reduce, so far as possible, these heat losses 25 through the neck or connecting bridge between the two shells; and further to accomplish this result without impairing the physical structure of the vessel or interfering 30 with the securing of the parts together by means of welded joints.

Another object of the invention is to so 35 construct the parts that the inner and outer shell may be held fixed in spaced relation wholly by means of the connection between the neck portions of the two shells.

In accomplishing the above named objects 40 I have found it desirable to use a connecting neck-piece between the inner and outer shells made of a material which is of greater thermal resistivity than the material of the shells. In the case of steel shells I have 45 found that a special alloy of nickel and copper (50% nickel and 50% copper) is well suited for the purposes of this thermal bridge in that it has the desired thermal resistivity and may be readily welded to the 50 metal of the shells. It is desirable however, that the interior of the inner shell of the bottle or receptacle, including the interior of the tubular member which constitutes the thermal insulating neck-piece connecting the 55 outer and inner shells, shall be provided with an enamel coat, having the characteristics and applied in the manner set forth in a pending application of Herbert M. Smith Serial No. 256,283. This enamel coat adheres well enough to the interior surface of

the inner steel shell, but some difficulty has been experienced in causing it to adhere to the surface of the alloy connecting piece. It is to overcome this objection that I have invented the method of treatment, including 60 the enameling step, hereinafter set forth.

Other objects and aims of the invention, more or less broad than those stated above, together with the advantages inherent, will be in part obvious and in part specifically 65 referred to in the course of the following description of the elements, combinations, arrangements of parts, and applications of principles constituting the invention; and the scope of protection contemplated will 70 appear from the claims.

In the accompanying drawing I have shown, in central vertical section, a vacuum bottle of the type with which my invention is concerned. Referring to the numerals on 75 this drawing, there is shown an outer shell 1 and an inner shell 2, the outer shell being closed at the bottom as shown, and the space between the shells providing an evacuated space, which may be filled with finely di- 80 vided insulated material indicated at 3. The upper or mouth end of the outer shell is re-duced as shown, and connecting the end of the outer shell, interiorly thereof, with the end of the inner shell 2, there is a tubular 85 connecting member indicated at 4, prefer-ably made of the alloy above referred to, or one having similar properties. The connec-tions between the bridge piece 4 and the in- 90 ner and outer shells are the welded joints 5 and 6, and it will be observed that the end of the inner shell is flanged to receive one end of the connecting member 4, while the extreme end of the outer shell is also re- 95 duced to a ring form so as to afford ample surface-to-surface contact between the outer shell and the connecting member. After the shells and the connecting member have 100 been connected together by means of the welded joints 5 and 6, the ground coat of enamel material, such as set forth in the Smith application above mentioned, is ap-plied to the interior of the inner shell, sub-stantially in the manner set forth in said 105 application, except that none of the ground coat material is allowed to remain on the in-terior surface of the connecting member 4, this surface being wiped clean before the ground coat is burned on. The article, with the ground coat material covering the in- 110

- terior of the inner shell, except for the connecting piece, as stated, is now put into a furnace and subjected to a heat of about 1800° F., substantially as described in the said 5 Smith application. The result of this treatment is to give the interior of the inner shell (except for the connecting member 4) a ground coat of enamel, and to oxidize the interior surface of the connecting member.
- 10 A second application of enamel material is now put on the entire inner surface of the inner shell, including also this time the interior of the neck piece, and the article is again put in the furnace and subjected to a 15 somewhat lower temperature, as described in the aforesaid Smith application, the result being to give the interior of the inner shell, except for the connecting member 4, a second enamel coat which adheres closely 20 to the ground coat thereunder, and to give to the interior of the connecting member 4 a coating of enamel which adheres to the surface of the connecting member by reason of the preliminary oxidation thereof above 25 described, and which is in the nature of a ground coat for the interior of the connecting member. A third coat of enamel may be applied if desired adhering to the second enamel coat of the body portion of the shell 30 and to the first coat of the connecting member.
- By following the operations above set forth I am enabled to utilize a connecting member having the desirable thermal resistivity and readily weldable to the metal of the shells, and can provide the neck piece with an enamel coating substantially uniform with the enamel coating of the body portion of the inner shell.
- 40 I claim:—
1. The method of constructing a vacuum receptacle, which comprises providing an outside shell having a bottom and a mouth portion, the mouth portion being of metal, 45 placing within and in spaced relation to the outer shell, a second but shorter shell with a metallic mouth portion and a closed bottom, connecting the neck portions of the two shells by welding to the mouth portions 50 thereof respectively the ends of a tubular connecting member made of a metal different from the metal of the mouth portions of the two shells and of higher thermal resistivity, but less adherent to an enamel or vitreous coat, whereby the connecting member 55 is an integral part of the inner shell and holds the two shells in spaced relation, treating the interior surface of the connecting member to render it more adherent to an enamel or vitreous coat, and applying a 60 continuous enamel or vitreous coat on the interior of the shell and connecting member.
  2. The method of constructing a vacuum receptacle, which comprises providing an outside shell having a bottom and a mouth portion, the mouth portion being of metal, 65 placing within and in spaced relation to the outer shell, a second but shorter shell with a metallic mouth portion and a closed bottom, connecting the neck portions of the two shells by welding to the mouth portions thereof respectively the ends of a tubular connecting member made of a metal different from the metal of the mouth portions of the two shells and of higher thermal resistivity, but less adherent to an enamel or vitreous coat, whereby the connecting member 70 is an integral part of the inner shell and holds the two shells in spaced relation, oxidizing the interior surface of the connecting member to render it more adherent to an enamel or vitreous coat, and applying a continuous enamel or vitreous coat on the interior of the shell and connecting member.
  3. The method of constructing a vacuum 75 receptacle, which comprises providing an outside shell having a bottom and a mouth portion, the mouth portion being of metal, placing within and in spaced relation to the outer shell, a second but shorter shell with a metallic mouth portion and a closed bottom, connecting the neck portions of the two shells by welding to the mouth portions thereof respectively the ends of a tubular connecting member made of a metal different from the metal of the mouth portions of the two shells and of higher thermal resistivity, but less adherent to an enamel or vitreous coat, whereby the connecting member 80 is an integral part of the inner shell and holds the two shells in spaced relation, oxidizing the interior surface of the connecting member to render it more adherent to an enamel or vitreous coat, and applying a continuous enamel or vitreous coat on the interior of the shell and connecting member.
